WORK FEEDING APPARATUS

William Cameron, Chicago, Ill., assignor to Cameron Can Machinery Co., Chicago, Ill., a corporation of Illinois

Application May 19, 1934, Serial No. 726,445

7 Claims. (Cl. 113—114)

This invention relates in general to can closing machines and the embodiment illustrated is a vacuum pack machine of the double seaming type.

5 Machines of this type heretofore in use have employed only a small vacuum chamber at the double seaming station. The filled body with the cap resting loosely thereon was introduced into this chamber and immediately moved into 10 cooperative relation with the double seaming mechanism, with the result that only an exceedingly small increment of time was allowed for drawing a vacuum on the interior of the can, and the production of the desired vacuum within the can was further impeded by the fact that the cap even before being clamped against the body rested more or less snugly thereon. Because of these 15 conditions the vacuum produced in the can before it was sealed varied in degree and was at best somewhat uncertain.

One of the purposes and advantages of my present invention is the provision of a large vacuum chamber in which the can bodies will be subjected to vacuum for a considerable period 20 of time before being sealed, and furthermore during this period the can end is maintained in spaced relation with respect to the body so that it will not impede or interfere with the production of a uniform vacuum of high degree in every 25 can before it is sealed.

Since can closing machines of this character are employed for closing cans containing liquid contents as well as dry contents, it is desirable that the filled can be handled, before it is sealed, 30 very gently as any sudden movements or change of direction will cause slopping and spilling of the contents. Another purpose of my invention, therefore, is to bring the filled cans to the double seaming station without shock, jar or sudden 35 movements, thereby obviating the slopping and spilling which is highly objectionable.

Another object of the invention is to provide a machine which may operate continuously irrespective of the regularity with which the filled 40 can bodies are fed to the machine, but which will be automatically stopped so as to prevent damage in the event that any spider pocket is not supplied with a can end before the pocket arrives at the can body receiving position. My invention 45 contemplates also control mechanism which precludes the feeding of a can end into a pocket in which an end is already contained.

Other features of my invention reside in improvements in the construction of the double 50 seaming mechanism and other parts of the ma-

chine, and in the general assembly and combination of mechanisms which enable the machine to operate with great rapidity, high efficiency, and with a minimum of attention, the construction being such that access to all the parts for 5 inspection and repair purposes may be readily had.

Other objects and advantages of my invention will be readily appreciated as the same become better understood by reference to the following 10 description when considered in connection with the accompanying drawings.

Referring to the drawings:

Fig. 1 is a longitudinal sectional view taken 15 on the line 1—1 of Fig. 4;

Fig. 2 is a fragmentary elevation viewed from the opposite side of the machine from Fig. 1, the feed conveyor being removed;

Fig. 3 is a vertical sectional view taken on the 20 line 3—3 of Fig. 1;

Fig. 4 is a top plan view of the machine;

Fig. 5 is a transverse sectional view taken on the line 5—5 of Fig. 4;

Fig. 6 is a fragmentary sectional view taken 25 on the line 6—6 of Fig. 1;

Fig. 7 is a similar view taken on the line 7—7 of Fig. 1;

Fig. 8 is a similar fragmentary view taken on the line 8—8 of Fig. 1;

Fig. 9 is a fragmentary sectional view taken on 30 the line 8—8 of Fig. 6;

Fig. 10 is a similar view taken on the line 10—10 of Fig. 6;

Fig. 11 is a diagrammatic view of the electric 35 circuit including the mechanism for breaking the circuit to stop the machine upon failure of the can end feeding mechanism;

Fig. 12 is a transverse sectional view taken on the line 12—12 of Fig. 4, the vacuum chamber being removed;

Fig. 13 is a fragmentary vertical sectional view 40 taken axially of the seaming head on the line 13—13 of Fig. 14;

Fig. 14 is a horizontal sectional view through the seaming head taken on the line 14—14 of 45 Fig. 13; and

Fig. 15 is a fragmentary vertical sectional view taken on the line 15—15 of Fig. 14.

Referring to the drawings more in detail and with particular reference to Figs. 1 and 4, it will 50 be observed that the machine comprises generally an elongated frame including a base portion 55 surmounted at one end by an upper portion 17 upon the top of which the driving motor 18 is mounted, the various operating mechanisms 55

of the machine being suitably mounted in or carried by this frame structure, as will be later explained more in detail.

The motor 18 constitutes the source of power for operating the various mechanisms and the lower end of its shaft is equipped with a driving pinion 19 meshing with a gear 21 fixed, together with a similar gear 22 of slightly smaller diameter, upon a hub or sleeve 23 which is splined 10 to the vertically disposed hollow shaft 24 which is journaled in upper and lower bearings 25 and 26, respectively, carried by the frame structure, and is provided at its lower end with a beveled pinion 27 meshing in driving relation with a 15 beveled gear 28 in turn fixed upon the main drive shaft 29 journaled in and extending longitudinally of the supporting frame structure.

Intermediate its ends the vertical shaft 24 is equipped with a worm 31 which drives a worm 20 wheel 32 fixed on the shaft 33 extending transversely of the machine and provided at its far end, viewing Fig. 1, with a sprocket wheel over which the endless conveyor 34 (Fig. 4) is trained and by which the filled can bodies 35 are fed in 25 succession to the left, viewing Fig. 4, from the machine by which the open top cans or bodies have been filled. The conveyor is continuously actuated, bringing the filled cans in succession to a point opposite the pusher 36 by which the 30 bodies are delivered to the spider or turret 37 in the following manner.

Referring now to Figs. 4 and 5, it will be observed that the pusher 36 is carried by an arm 38 in turn supported upon a post 39 which is 35 carried at one end of a slide bar 41 adapted to be reciprocated transversely of the machine. A guide bar 42 secured by bolts 43, or otherwise, to the bottom of bar 41 is guided in its reciprocatory movements in a guide-way indicated 40 generally by reference character 44. Reciprocatory movements are imparted to the slide bar by a connecting rod 45 (Figs. 3 and 5) connected with the bar by a bolt 46 and at its other end to a crank pin 47 carried by a crank 48 fixed 45 upon the upper end of a vertically disposed shaft 49. This shaft is provided at its lower end with a beveled gear 51 (Fig. 1) which is driven from a companion gear 52 fixed on the horizontal drive shaft 29. At each revolution of the shaft 50 49 a complete reciprocation of the slide bar 41 is effected to transfer a filled can body laterally from the conveyor 34 on to a lifting chuck beneath the turret spider as will now be explained.

In proximity to the conveyor and in the line of 55 the pusher 36 is disposed a vertically reciprocable chuck head 53 mounted upon the upper end of a rod or post 54 adapted to reciprocate in suitable bearings 55, the post being elevated at timed intervals by the lever 56 fulcrumed at 57 and 60 yieldingly actuated to elevate the chuck by a spring 58. The lever is positively actuated in the opposite direction to lower the chuck by a cam 59 against which the cam follower 61 is held by the spring 58, the cam 59 being mounted upon 65 a shaft 62 (Figs. 1 and 2) which is driven through a chain 63 from the transverse shaft 64. The shaft 64 is driven from shaft 29 through a pair of meshing beveled gears 65 and 66, respectively.

The cam 59 is designed to dispose the upper 70 face of the chuck 53 on a level with the conveyor 34 at the time the pusher 36 is being moved to the left, viewing Fig. 5, to slide the filled can body 35 on to the chuck. The transfer of the body from the conveyor on to the chuck is effected while the body is being carried forward

by the conveyor so that no abrupt stopping of the travel or abrupt change of direction is produced which would tend to cause slopping or spilling of the can contents. For the same reason the chuck 53 is gradually moved upwardly before the can body has been fully positioned thereon. It will be apparent, therefore, that both the lateral transfer and the elevation of the filled can body are accomplished simultaneously and by a gradual movement so that the body travels in a lateral and upwardly inclined curve in its movement from the conveyor to the turret, the entire movement being effected gradually and without agitation of the can.

The turret comprises a stationary plate 67 (Figs. 5 and 12) forming the bottom of the turret above which mounted concentrically therewith upon the upper end of the vertical shaft 68 is disposed the spider 37 provided with a series of radially arranged can body receiving recesses or pockets 69. Immediately above the chuck 53 the plate 67 is cut away so as to provide an opening for the reception of the can bodies. As a body is moved from the conveyor on to the chuck 53 and is elevated by this chuck it enters the opening in the plate 67 and one of the pockets 69, as illustrated in Fig. 12, so that upon rotation of the spider 37 the body is carried along thereby off from the chuck 53 on to the plate 67.

The spider is rotated in a step by step movement by mechanism best illustrated in Figs. 1 and 3. From these figures it will be seen that the spider 37 is bolted to a collar 71 fixed upon the upper end of shaft 68 which carries intermediate its ends the driven wheel 72 of a Geneva motion, the driving member of which comprises a pin 73 carried by an arm 74 fixed on the shaft 49 so that with each revolution of shaft 49 a partial rotation of shaft 68 and the spider 37 carried thereby is produced.

The intermittent movement of the spider takes place in a counterclockwise direction, viewing Figs. 4, 6 and 7, and the can bodies delivered to the turret from the feed-in conveyor are moved by the spider into the vacuum chamber where the caps are double seamed on to the body in a manner which will be later explained.

Before the bodies are delivered into their respective pockets of the spider, each pocket has been supplied with a can end adapted to be double seamed on to the body. The mechanism for supplying the spider pockets with ends is best illustrated in Figs. 1 and 4, from which it will be observed that the ends, indicated by reference character 75, are stacked in a magazine above a reciprocating slide 76 by which the ends are transferred in succession from the magazine to an aligned spider pocket. The details of the transfer slide and mechanism for separating the can ends from the magazine may be of any well-known or preferred type and are not here illustrated. It is sufficient for present purposes to state that the slide is reciprocated by means of a lever 77 fulcrumed upon the frame structure at 78, which lever receives its feeding movement from a tractive spring 79 and is returned by a cam 81 on the shaft 62. At each actuation of slide 76 a can end is removed from the magazine and transferred to a position beneath the marking device 82 disposed above the path of travel of the ends. The lower face of the marking device is equipped with a marking die and at the marking station the end is elevated by a chuck carried by the upper end of plunger 83 into marking engagement with the die. This plunger 1

yieldingly held down by a spring 84 and is positively elevated by a lever 85 fulcrumed at 86 and actuated by a cam 87 also mounted on shaft 62. At the next actuation of the slide 76, the marked end is transferred from the marking station to the spider and another end from the magazine replaces the one removed from the marking station.

From Figs. 6 and 12 it will be apparent that the upper end of each spider pocket 69 is shaped to provide a pair of supporting guides 88 forming a supporting shoulder upon which an end is supported above and in alignment with a can body. In order to hold the positioned ends against dis- placement from alignment with their corresponding bodies, spring pressed pivoted dogs 89 are employed, one at each side of the supporting shoulder, the inner ends of these dogs being urged toward each other by springs 91 (Figs. 6 and 9) to press against the can end outwardly of its center, so as to urge the end into the pocket and retain it in that position. Beneath each shoulder 88 the socket is shaped to provide an upwardly tapered annular surface 92 which, as the can body is elevated, rounds up the body and centers it with respect to the positioned end.

As the can bodies with their superposed ends are moved by the spider away from the chuck 53, they enter the vacuum chamber in which the air is exhausted from the cans before the ends are double seamed thereon, as will presently appear. The vacuum chamber is formed by an air-tight housing partially encompassing the spider 37. A segment 93 of this housing overlies the spider and is urged into hermetic sealing relation therewith by springs 94 which press the segment down against the spider. A removable segment 95 of the housing abuts the segment 93 to which it is clamped by bolts 96. Upon removal of these bolts the segment 95 may be removed to permit access to the enclosed seaming head. The bottom of the vacuum chamber is formed by the turret base plate 67 which is urged against the lower face of the spider by springs 97 (Fig. 1), one of which is shown as being interposed between the lower face of the plate and an arm 98 adjustably supported by a collar 99 threaded upon the upper end of the shaft bearing 101. A stud 102 carried by the arm cooperates with a socket in the plate to hold the plate against rotation.

Outside the perimeter of the spider the lower portion of the vacuum chamber is formed by a stationary segment 103 against which the removable segment 95 is urged into sealing relation by springs 104, one of which is illustrated in Fig. 1. A packing or seal ring 105 is interposed between the springs 94 and 104 and the tops of the chamber segments 93 and 95 to insure an air seal at the top of the chamber. Vacuum is applied to the chamber through a pipe 106 connected with a conveniently located vacuum pump (not shown). The vacuum chamber as a whole is urged in sealing relation with the periphery of the spider by springs 107 acting against plungers 108 (Fig. 7) engaged with projections 109 from the chamber wall. The plungers also serve as latches to hold the chamber in position. By re-tracting these latches to inoperative position, the chamber is released for removal if necessary. These latches, as will be apparent, are carried by an upright portion 111 of the frame structure.

As the can bodies with their superposed ends are moved in succession into the vacuum chamber, they are brought over the chuck 112 (Figs.

1 and 6) by which they are elevated into cooperative relation with the seaming head above. This chuck, as will be seen from Fig. 1, is carried upon the upper end of a lost motion stem comprising the sleeve 113 and the rod 114 having a pin and slot confection 115 with an interposed spring 116, the yieldability of which protects the bodies and the mechanism against injury from excessive upward movement of the stem, and at the same time insures a snug engagement with the seaming head. The rod 114 is actuated by a cam follower 117 which is operated from a face cam 118 mounted on the shaft 29. The chuck 112 has a close sliding fit with the surrounding guide walls so as to form a substantially air-tight seal around the chuck. During the travel of the can body within the vacuum chamber to the chuck 112 and during the elevation of the chuck, the body and its contents are subjected to the action of a vacuum so that when the cap is double seamed on to the body, forming a hermetic seal therefor, the contents of the can are sealed up under a substantial vacuum. Deterioration of the can contents resulting from the presence of air in the can is accordingly precluded.

When the body is elevated by the chuck 112, the upper edge of the body engages and carries upwardly with it the superposed can end 75, the body and end being snugly clamped together between the seaming chuck 119 and the lifting chuck 112, the spring 116 serving to insure such clamping action without injury to the can or end.

The seaming chuck is carried upon the lower end of a tube or sleeve 121 suspended within the vertical guide bearing 122. This sleeve is provided near its lower end with an annular shoulder 123 supporting the lower race 124 of a ball bearing, the upper race 125 of which supports the sleeve 126 surrounding the sleeve or tube 121. The seaming head block 127 is securely attached by bolts, not shown, to the sleeve 126 so as to be rotated thereby. The sleeve 126 itself is rotated by a gear 128 keyed to its upper end and meshing with the driving gear 21.

A second sleeve 129 carried by and rotatable relatively to the sleeve 126 is connected at its upper end to and is rotated with a gear 131 which meshes with and is driven by the drive gear 22. The lower end of sleeve 129 is outwardly flanged and shaped to provide a cam 132 which actuates the final seaming rollers and a second cam 133 fixed to the sleeve 129 serves to actuate the preliminary seaming rollers in a manner presently explained.

The head block 127 carries a pair of opposite disposed parallel fulcrum pins 134 upon which the arms 135 are respectively fulcrumed. Each of these arms carries at its lower end a primary seaming roll 136 adapted to cooperate with the chuck 119 in performing the preliminary seaming operation, and at its upper end a rotatable cam follower 137 engaging the face of the cam 133 by which the arms 135 are rocked on their fulcrums to move the seaming rolls 136 into operative relation to the chuck 119. The expansion springs 138 interposed between the lower portion of the arm and the block 127 exert an outward thrust upon these arms in opposition to the thrust exerted by the cam 133.

The head block 127 carries also a second pair of oppositely disposed parallel fulcrum pins 139 upon which the arms 141 carrying the final seaming rollers 142 are fulcrumed. The upper end of each of these arms is provided with a cam follower 143 which is maintained in contact with

the cam 132 by an expansion spring 144 similar to the springs 138. In order to provide for flexibility in the arms sufficient to prevent injury to the can bodies and caps, which might be produced by excessive pressure of the final seaming rollers 142, arms 141 are transversely cut as indicated at 145 (Fig. 13) and slight yieldability between the two thus separated portions of the arms is afforded by a strong expansion spring 146 interposed between lateral extensions of the arms 147 and 148. Adjustability of the parts to a fine degree of accuracy is afforded by the adjustable nut 149 on the connecting bolt 151.

In operation the head block carrying the seaming rollers is constantly revolved at a high rate of speed by the gears 21 and 128, while the sleeve 129 carrying the cams 132 and 133 is continuously revolved at a somewhat slower speed by the gears 22 and 131. The timing and the contour of the cams 132 and 133 are such that the preliminary seaming rollers are moved toward the chuck 119 to perform the preliminary seaming operation, whereupon these rollers are withdrawn and the final seaming rollers 142 are brought into operation to complete the double seaming of the cap on to the body.

When the can has been closed under vacuum in the manner described, the chuck 112 is lowered into the plane of the bottom plate 67 of the turret. To insure that the end will be freed from the chuck 119, a pusher or knock-out head 152 is carried in the chuck 119 by the lower end of a rod 153 which receives a downward thrust to free the can end from the chuck simultaneously with the lowering of the chuck 112. This movement of the knock-out rod 153 is effected by a lever 154 connected at 155 (Fig. 1) with the knock-out rod and fulcrumed at 156 upon the machine frame. The lever is oscillated by a rod 157 extending downwardly through the hollow shaft 24 and provided at its lower end with a reciprocating head straddling the shaft 29 and carrying a laterally projecting cam follower 158 which travels in the cam race 159 of a face cam 161 keyed to the shaft 29.

When the chuck 112 has been lowered into the plane of the base plate 67 of the turret, the closed can is moved by two successive movements of the spider into a position over a vertically reciprocable chuck 162 (Figs. 6, 7 and 12) which at such time is in its uppermost position in alignment with the plate 67 which is provided with an opening 163 for the reception of the chuck similar to the opening on the opposite side for the reception of the elevating chuck 53. When the body has been positioned upon the chuck 162, this chuck is lowered into the position shown in Fig. 12, thereby lowering the body into position to be engaged by a pusher 164 by which the body is pushed horizontally out of the turret.

It should be mentioned that for the purpose of insuring proper centering of the body and superposed end with respect to the seaming chuck 119 when the body and end are elevated into seaming position by the chuck 112, the lower face of the head block 127 is provided between the circumferentially spaced seaming rolls with arcuate guide ribs 165 (Figs. 14 and 15), the inner faces of which are inclined or chamfered off, as indicated at 166, to guide and center the cap and body in proper cooperative relation to the seaming chuck 119.

Returning now to the delivery of the closed and sealed can from the turret, the pusher 164 is carried, as will be apparent from Fig. 5, upon a post

160 fixed to the slide bar 41 which, as previously explained, also carries the pusher 36. Upon movement of this slide bar to the left viewing Fig. 5, not only will a can body be transferred by the pusher 36 from the conveyor 34 on to the chuck 53 as previously explained but simultaneously a closed can will be transferred from the chuck 162 on to an adjacent delivery conveyor 170 which, as shown in Fig. 4, conveys the cans to the delivery end of the machine. The chuck 162 is carried upon a post 167 which is raised and lowered in suitable timed relation by an ordinary cam device, not shown.

Since the filled can bodies may not be fed to the machine with regularity and since the machine as a whole, including the turret spider, is continuously operated, it frequently happens that a spider pocket supplied with a can end but with no can body enters the vacuum chamber. In that event, no body being positioned upon the chuck 112, the elevation of this chuck will not displace the can end from its position in the spider and the seaming rolls will operate idly. The can end, therefore, is carried out of the vacuum chamber by the spider and continues to travel around with the spider. When this pocket already supplied with a can end reaches a position in alignment with the can end feeding mechanism where it would normally be supplied with an end, provision is made to preclude the delivery of another end to this already supplied pocket or otherwise obviously damaging results would ensue. With this end in view I have provided mechanism for rendering the can end feed inoperative whenever a spider pocket already containing an end is brought into cooperative relation with the can end feeding mechanism.

Viewing Figs. 1 and 4, it will be observed that, as each spider pocket reaches a position immediately preceding that in which a can end would normally be delivered to it, a detector comprising a feeler finger 180 carried by an arm 168 mounted upon the upper end of a reciprocatory rod 169 is moved downwardly into the pocket. This movement is effected by a spring 171 which pulls downwardly upon that end of a lever 172 which is attached to the lower end of rod 169. The lever is fulcrumed on the frame structure at 173 and is equipped with a cam follower 174 which rides upon a cam 175. Beyond its fulcrum 173 this lever is extended as shown at 176 into the path of an abutment 177 carried by the cap feed slide operating lever 71.

If, as would normally happen, the feeler finger encounters no cap in the spider socket, the lever 172 is permitted by its cam to be rocked in a counterclockwise direction, viewing Fig. 1, sufficiently low to clear the extension in the path of the abutment 177. In that event a normal cap feeding operation will be performed. Should, however, the feeler finger 180 contact a cap in the spider pocket, downward movement of the rod and consequently counterclockwise movement of the lever 172 is arrested so that the extension 176 is retained in the path of the abutment 177 whereby a feeding movement of this lever under the influence of spring 171 is precluded. No end, therefore, is delivered to a spider pocket in which an end is already positioned.

The machine of this invention also makes provision for assurance against the possibility of a can body being delivered into the turret without a corresponding end positioned in the turret for assembly with the body. Should any spider pocket fail to be supplied with a can end, which

might result from failure of the supply of ends in the magazine or from failure of the can end feeding mechanism to properly operate, and should this pocket receive a filled can body and should this body without a corresponding end be delivered to the double seaming station, unfortunate results would ensue. Manifestly if a filled body without any superposed end were elevated into position to be operated upon by the seaming rolls, the can body would be jammed and distorted by these rolls, it could not be freed from the seaming chuck by the knock-out device, and a jam in the machine and also considerable spilling of the can contents in the vacuum chamber would result. To obviate such difficulties my machine has provision for automatically stopping the machine as a whole whenever a spider pocket is not supplied with a can end before the entrance of that pocket into the vacuum chamber.

Referring now to Figs. 2, 4, and 11, it will be observed that beyond the can end supplying station a second detector comprising a feeler finger 178 carried by an arm 179 mounted upon the upper end of a vertically reciprocable post is arranged with the feeler finger in vertical alignment with a spider socket. The lower end of the post 181 is pivotally connected at 182 with a lever 183 fulcrumed at 184 and provided with a cam follower 185 which is urged against its actuating cam 186 by a tractile spring 187.

As the spider pockets are brought into position beneath the feeler finger 178, the contour of the cam 186 permits the post 181 and the detector carried thereby to be lowered by a spring 187 into the pocket. If the pocket contains a can end as it should, downward movement of the feeler finger is arrested by the can end and the operation of the machine is permitted to continue, the detector being lifted by the cam 186 from engagement with the can end prior to the next forward step of the turret spider.

Should there be no can end in the pocket, however, downward movement of the detector and the lever 183 will continue, causing a thrust member 188 carried by the rod 189 suspended from the lever 183 to engage and depress an opposed thrust member 191, thereby opening an electric circuit to cause the supply current to the main driving motor 18 to be shut off. The entire machine is thus stopped so that the operator may remedy the defect by manually inserting a can end in the empty pocket before the machine is again started.

The control of the main motor by the detector may be effected through any suitable arrangement, but in Fig. 11 I have illustrated diagrammatically one suitable arrangement for this purpose. In this figure the main supply circuit to the motor 18 comprising the lead lines 192 and 193 includes a switch member 194 which is urged to open position by a spring 195. A shunt circuit 196 including a primary winding 197 induces through a secondary winding 198 a current in a secondary circuit in which is included a switch 199 controlled by the thrust member 191, and an electromagnet 201 adapted to hold the switch member 194 in closed position. Upon depression of the thrust member 191 by the opposed thrust member 198 under the influence of spring 197 the switch 199 is opened thereby deenergizing the electromagnet 201 to permit breaking of the main circuit by the opening of the switch 194, thereby stopping the drive motor.

It will be apparent, therefore, that the ma-

chine is automatically controlled so as to prevent the feeding of a can end into a spider pocket which already contains an end, and also to prevent the entrance of a spider pocket into the vacuum chamber unless it is supplied with a can end. The machine is accordingly capable of operating continuously irrespective of whether can bodies are conveyed continuously to it or not, but in the event of failure of a can end to be positioned in a pocket the machine is immediately stopped.

In order that the operator may always be aware of the amount of vacuum being produced in the vacuum chamber, this chamber is equipped with a vacuum gauge 202 (Fig. 1) mounted at any conveniently visible position. In order that the machine may be turned over by hand for test and inspection purposes, a hand wheel (not shown) is mounted at one side of the machine on the projecting end of a shaft 203 (Fig. 1) upon which is fixed a worm 204 meshing with a worm wheel 205 on the main vertical drive shaft 24.

The operation of the machine having been explained in connection with the foregoing description of the parts, a brief résumé only of the 25 operation will be given.

The filled can bodies are brought in succession by the continuously operating feeding conveyor 34 from which they are transferred laterally by the pusher 36 on to the elevating chuck 30 53 by which they are lifted in succession into the vacuum chamber where, after being subjected to the vacuum therein, they are sealed by having the can ends double seamed thereunto by the double seaming mechanism. From the double 35 seaming station they are conveyed out of the vacuum chamber to a point where they are permitted to drop through an opening in the bottom plate of the turret, the lowering movement being controlled by the chuck 162 from which 40 they are transferred by the pusher 164 on to the delivery conveyor 166. The spider turret pockets are supplied in succession with can ends by the can end feeding mechanism, the operation of which is temporarily stopped whenever a pocket 45 which already contains a can end is brought into registration with the feed mechanism.

Should a pocket fail to be supplied with a can end, this fact is automatically determined by the machine which is immediately shut off in that 50 event so as to preclude the entrance of a can body into the vacuum chamber unless a corresponding can end is in position to be double seamed on to the bottom.

The details of construction illustrated and described are obviously capable of various modifications without departing from the spirit of the invention as defined in the following claims.

I claim:

1. In a can closing machine, the combination of 60 a spider adapted to receive can bodies, a continuously operating conveyor, a pusher movable transversely of the conveyor, a can chuck movable vertically toward and from said spider, and means operating said pusher and said chuck in such 65 timed relation that a can body is moved from the conveyor through a curved path onto said chuck while still traveling with the conveyor, and is moved upwardly by the chuck through a curved path while it is still being moved transversely by 70 the pusher.

2. In a can closing machine, the combination of a rotatable turret spider, a can closing mechanism positioned in cooperative relation to said spider, a chuck for inserting can bodies into said 75

- spider, a chuck upon which the can bodies are removed from said spider, a feed-in conveyor in proximity to said first chuck, a delivery conveyor in proximity to said second chuck, a pair of pushers, a reciprocatory slide carrying said pushers, and means for actuating said slide to transfer a can body from said feed-in conveyor to said first chuck and simultaneously transfer another body from said second chuck to the delivery conveyor.
10. 3. A can body closing machine comprising a rotatable turret spider provided with can body and can end receiving pockets, a can closing mechanism disposed in cooperative relation to said spider, a feed-in conveyor at one side of the 15 spider, a delivery conveyor at the opposite side, a chuck disposed beneath the spider adjacent to said feed-in conveyor, a second chuck disposed beneath the spider adjacent to said delivery conveyor, means for raising and lowering said chucks 20 in synchronism, and means including a slide provided with a plurality of pushers for transferring can bodies from the feed-in conveyor to said first chuck and from said second chuck to said delivery conveyor.
25. 4. In a can end closing machine, the combination of a spider provided with pockets for the reception of can bodies and ends, a can closing mechanism, means for feeding can bodies and ends to said pockets, means for preventing the 30 feeding of a can end to a pocket in which an end is already disposed, an electric motor for driving the spider and feeding means, and means for stopping the motor to prevent the delivery of a body to the closing mechanism in the event that 35 the pocket in which said body is disposed contains no end for attachment thereto.
5. In a can closing machine, an intermittently operated turret provided with can body receiving pockets, a continuously operating conveyor for

delivering can bodies into proximity to said turret, and means for moving said bodies by a continuous motion through a curved path from said conveyor to said turret without abrupt change in speed or direction, whereby spilling of the body contents is obviated, said means including a reciprocating member for changing the direction of travel of said bodies during the advancing movement thereof by said conveyor.

6. In a can closing machine, the combination 10 of a rotatable turret provided with can body receiving pockets, a continuously operating conveyor, a laterally movable pusher, a vertically movable chuck, and means for operating said conveyor, pusher and chuck in such timed relation as to transfer can bodies by a continuous movement from said conveyor to said turret by moving said bodies horizontally in a curved path away from said transfer and then elevating said bodies through a curved path into said 20 spider, said movements being effected without abrupt change in speed or direction of the bodies, whereby spilling of the body contents is obviated.

7. In a can closing machine, the combination of an intermittently operated turret provided 25 with can receiving pockets, a continuously operating conveyor for conveying can bodies to said turret, and means for transferring said bodies from said conveyor to said turret, said means including a reciprocatory member operable in 30 timed relation with the advancing movement of the bodies for gradually changing the direction of such movement so as to direct the bodies in a continuous curved path into the turret pockets without abrupt change in speed or direction 35 whereby to obviate spilling of the contents of said bodies.

WILLIAM CAMERON.
